UNITED STATES PATENT OFFICE

2,486,604

ELECTRIC IRON REST

Irving J. Kopel, Chicago, Ill.

Application January 24, 1947, Serial No. 724,125

1 Claim. (Cl. 248—117.3)

1

This invention relates to an iron rest or support which is particularly adapted for use in supporting an electric iron.

The primary object of the present invention is to provide a new and improved and relatively simple and inexpensive iron rest for electric irons.

An additional object of the invention is to provide an electric iron rest embodying a base or pad of non-combustible heat-insulating material such, for example, as felted asbestos, a sheet metal top having formed integrally therewith a marginal edge portion or bead for preventing the iron from slipping off the said sheet metal top, and novel fastening elements formed integral with the sheet metal top for securely fastening the base or pad of non-combustible heat-insulating material to the overlying sheet metal top.

Other and further objects of the present invention will be apparent from the following description and claims and are illustrated in the accompanying drawing which, by way of illustration, shows a preferred embodiment of the present invention and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claim.

In the drawing:

Fig. 1 is a top plan view of the new electric iron rest;

Fig. 2 is a central longitudinal sectional view on line 2—2 in Fig. 1;

Fig. 3 is a bottom plan view of the new electric iron rest; and

Fig. 4 is an enlarged sectional detail view on line 4—4 in Fig. 1.

A preferred embodiment of the new electric iron rest is illustrated in the drawing, wherein it is generally indicated at 10, and comprises a suitably shaped sheet metal top 11 embodying a substantially uniplanar flat body 17 and a correspondingly shaped base 12 of non-combustible heat-insulating material such, for example, as felted asbestos formed and compressed into sheet or board form and out to the desired shape.

The sheet metal top 11 has an upraised retaining bead 13 formed therein and extending around its marginal edge above the plane of the flat, uniplanar body 17 of the top 11 and this retaining bead 13 has an outside wall 14 which

2

extends downwardly part way over the outside marginal edge of the base 12.

In order to securely fasten the base 12 to the top 11 I provide, at suitably spaced intervals around the sheet metal top 11, a plurality of fastening elements 18. Each of the fastening elements 18 includes a depending arm 15 which is formed as an integral downward extension of the outside wall 14 of the sheet metal top 11. Each of the fastening elements 18 also includes an inwardly and horizontally extending tongue 16 which is formed as an integral extension of the corresponding one of the depending arms 15. As shown in the drawing, these fastening tongues 16 extend under the base 12 and securely fasten the base 12 and the top 11 together as a unit so that they may be readily handled and used as a unit and without separation.

In the manufacture of the new electric iron rest the sheet metal top 11 may be formed of a suitable quality of sheet metal stock, such, for example, as sheet steel, of suitable gauge, and in any suitable manner, as by means of a stamping operation, and so that the sheet metal top 11 embodies the fastening elements 18—15—16 formed as integral parts thereof. The thus formed sheet may be provided in any suitable manner, as by means of a suitable forming die, with the retaining bead 13. The top 11 and base 12 may then be assembled with the base 12 arranged within the marginal edge of the outer wall 14 of the retaining bead 13, whereupon the tongues 16 of the fastening elements 18 may be bent inwardly, in any suitable manner, so as to underlie the base 12 in substantially parallel relation thereto, thus completing the assembly of the top 11 and base 12 and the fastening of these parts together into a unitary structure.

In the use of the new electric iron rest the same may be supported upon an ironing board, or other suitable support, and when so supported an electric iron may be placed upon the substantially flat and uniplanar body 17 of the sheet metal top upon which it will be retained by the upright retaining bead 14 which provides a marginal retaining wall around the body 17 of the sheet metal top 11 so as to retain the electric iron against sliding off the same.

It will thus be seen from the foregoing description, considered in conjunction with the accompanying drawing, that the present invention provides a new and improved and relatively simple and inexpensive electric iron rest having the advantages and desirable characteristics, and accomplishing its intended objects, including

those hereinbefore pointed out and others which are inherent in the invention.

I claim:

An electric iron rest comprised of an oval-shaped sheet metal top including a substantially flat, uniplanar body having an upraised bead formed integral therewith and extending around its marginal edge above the plane of the said substantially flat, uniplanar body of the top and providing a marginal retaining wall therearound, a substantially flat oval-shaped base of non-combustible heat-insulating material disposed below the said top within the said outer marginal wall thereof and having the said substantially flat and uniplanar body of the said oval-shaped sheet metal top resting thereon, and means formed integrally with and as a part of the said oval-shaped sheet metal top for fastening the said oval-shaped base and the said oval-shaped sheet metal top together into a unitary structure, said fastening means consisting of a plurality of relatively narrow spaced metal fastening elements formed integral with and as extensions of the said outer wall of the said bead and arranged at intervals therearound, each of the said fastening elements including a portion extending in-

wardly relative to and at substantially a right angle to a corresponding one of the said depending extensions of the said bead and under the said oval-shaped base in contact with and substantially parallel to the bottom surface thereof, the said substantially flat, uniplanar body of the said sheet metal top and the said depending extensions of the said bead and the said inwardly extending portions thereof cooperating to provide channels for the reception of marginal edge portions of the said substantially flat oval-shaped base.

IRVING J. KOPEL.
